UNITED STATES PATENT OFFICE.

DAVID W. OVAITT, OF FLINT, MICHIGAN.

TELEPHONE STAND.

Application filed October 2, 1922. Serial No. 591,918.

The invention relates to a stand for telephones and has for some of its objects the provision of a safety stand which supports a removable telephone but prevents accidental disengagement of the telephone; the provision of a stand which is arranged to permit of the disengagement of the telephone only upon the combined upward and forward movement thereof; the provision of a stand supporting a spring to which an extensible cord for a telephone book or the like is secured whereby the telephone book or the like will normally occupy a position in immediate proximity to the stand, but may be withdrawn a limited distance to be more readily accessible; and the provision of a stand provided with a light in close proximity to and guarded by the stand. Other objects of the invention reside in the novel features of construction and combinations and arrangements of parts as more fully hereinafter set forth.

In the drawings:

Figure 1 is a plan view of a telephone stand or support embodying my invention;

Figure 2 is a front elevation thereof;

Figure 3 is a cross section on the line 3-3 of Figure 1;

Figure 4 is a plan view of the brace of the stand;

Figure 5 is a perspective view of the stand showing the telephone and light cords.

1 is the shelf of the stand provided with a peripheral upwardly extending wall 2 around the sides and rear, the front ends of this wall having upwardly and rearwardly inclined edges extending from points on the shelf at less distance apart than the diameter of the base 3 of the telephone, the distance between the upper portions of the inclined edges being greater than the diameter of the telephone base. This wall has the inturned ears 4, extending from its upper edges at the opposite sides of the shelf to lie over the telephone base and prevent its removal from the shelf in an upward direction. The arrangement of the ears and inclined edges is such that the telephone base may be removed from the shelf only by tilting the telephone rearwardly and moving its base in a combined upward and forward direction.

The shelf has the depressed portion 5 of progressively increasing depth extending from its center and the aperture 6 at the rear end of the depression for receiving the

telephone cord 7, and the wall 2 is cut away at 8 for the insertion of the telephone cord prior to the securing of the shelf to a side wall by the screws 9 passing through the wall on opposite sides of the cut away portion.

10 is a rearwardly and downwardly inclined brace adapted to be secured at its lower end to the side wall by the screw 11 and secured at its upper end to the centrally located depending flanges 12 upon the shelf and extending transversely thereof by the bolts 13. This brace has the recess 14 in the upper face and the upwardly extending post 15 located axially within the recess. 16 is a reel having the hollow cylindrical body 17 and the annular upper and lower flanges 18 and 19, this reel engaging in the recess 14 and being rotatable about the axial pin 20 threaded in the post 15. The reel is yieldably held in its normal position of rotation by the coil spring 21 having the square inner end 22 engaging the square upper end 23 of the post 15 and having the eye 24 at its outer end through which the pin 25 passes, this pin being secured in the boss 26 upon the inner side of the hollow body 17 of the reel.

27 is a suitable cord such as a flexible beaded cord or a link chain having one end passing through and secured to the hollow body 17 of the reel and the other end secured to a telephone book or the like 28, this cord passing through the hollow gripping member 29 having a press fit in the front end of the brace 10. This gripping member has the vertical slot 30 in the lower wall of its nose or front end which is of a width to grip the cord when lowered thereinto and has the enlarged opening 31 in the upper wall for permitting of the free movement of the cord when engaging therein. The arrangement is such that when the telephone book or the like is in immediate proximity to the stand and below the same, the cord is in the slot and held from longitudinal movement. However, upon lifting the telephone book or the like and pulling the same outwardly, the cord is raised out of the slot into the enlarged opening when the cord may move longitudinally, so that the telephone book or the like may be more accessible. After the telephone book or the like has been pulled outwardly a sufficient distance, a downward movement thereof with the cord will move the cord into the slot when it will then be gripped and any tension upon the cord ex-

erted by the coil spring removed. When the party using the telephone book or the like has finished, the latter can be returned to a position in close proximity to and below the telephone stand by moving the cord upwardly to bring the same into the enlarged opening, after which the coil spring will rotate the reel back to its normal position of rotation, thereby winding the cord upon its cylindrical body between the two annular flanges. After the telephone book or the like has been returned to its normal position, the cord may then be lowered into the slot when the cord will then be held from longitudinal movement.

For the purpose of providing illumination to read the telephone book or the like, there is the elongated incandescent bulb 32 extending transversely of and immediately below the shelf 1, this bulb being mounted at the inner end of the transversely extending end of the pipe 33 having an end extending longitudinally of and at the side of the shelf and within the lug 34. The electrical cord 25 for the incandescent bulb extends through this pipe and leads from a suitable base plug in the side wall. 35 is a set screw extending upwardly in the lug 34, and adapted to engage the pipe to lock the same with its transversely extending end in horizontal position. Upon releasing the set screw the pipe can be rotated to bring the transversely extending end into substantially vertical position so that the incandescent bulb may be readily 30 removed and replaced. To guard the incandescent bulb and at the same time prevent its light rays from extending laterally out and upwardly, there is the depending peripheral flange 36 upon the shelf 1 extending from the front around both sides and to the rear, this flange being cutaway at 37 for the passage of the pipe 33.

To temporarily support the telephone receiver, I have provided the fork 38 secured to the side of the lug 34 by the screw 39, and extending forwardly thereof.

From the above description it will be readily seen that I have provided a safety stand for a telephone which prevents accidental disengagement of the telephone but permits of its removal upon a combined upward and forward movement. Also, that I have provided an extensible cord for a telephone book or the like which is normally wound upon a reel. Furthermore, that a source of illumination to read the telephone book or the like is provided below the shelf of the stand and guarded by a depending flange which also prevents the light rays from rising. Still another feature resides in forming a depression in the shelf to receive the telephone cord when the telephone is being returned to the stand after use whereby possibility of the telephone cord becoming twisted is precluded owing to the fact that the tele-

phone is returned upon the stand in the direction opposite that taken during its removal. With this particular arrangement of shelf, the telephone cord will not interfere with the removal or replacement of the telephone; and furthermore, when the telephone is supported upon the stand, the telephone cord extends in close proximity to the side wall, thereby minimizing the possibility of the cord becoming tangled or interfering with moving objects.

What I claim as my invention is:

1. In a telephone stand, the combination with a horizontally extending shelf, of an upwardly extending wall for partially surrounding the base of a telephone, the front ends of said wall having upwardly and rearwardly inclined edges extending from points on the shelf at less distance apart than the diameter of the base of the telephone, the distance between the upper portions of the inclined edges being greater than the diameter of the base of the telephone, whereby horizontal movement of the telephone in any direction with respect to the shelf is prevented without first guiding the forward edge of the telephone base between said upper portions of the inclined edges of the wall, and ears upon opposite sides of said wall overlying the base of the telephone.

2. In a telephone stand, the combination with a horizontal shelf, of an upwardly extending peripheral wall upon said shelf for partially surrounding the base of a telephone, the front ends of said wall having rearwardly and upwardly inclined edges extending from points upon said shelf, the distance between which is less than the diameter of the base of the telephone whereby the base of the telephone cannot be moved in a horizontal plane in any direction along the surface of the shelf, the distance between the upper portions of said inclined edges being greater than the diameter of the base of the telephone for permitting passage of said base therethrough, and means upon said wall and formed integrally therewith overlying the base of the telephone for preventing its upward movement.

3. In a telephone stand, the combination with a horizontally extending rigid shelf, of an upwardly extending wall for partially surrounding the base of the telephone, the front ends of said wall having upwardly and rearwardly inclined edges extending from points of the shelf at less distances apart than the diameter of the telephone base, the distance between the upper portions of the inclined edges being greater than the diameter of the telephone base, and ears upon opposite sides of said wall overlying the base of the telephone.

4. A telephone stand having a member provided with an opening formed with a slot, a cord engageable with said slot at a plural-

ity of points along the length of the cord and passing freely through said opening for connection with a telephone book, the width of said slot being such as to engage the cord 5 when the latter is positioned for engagement with the slot to prevent lengthwise movement of the cord.

5. The combination with a telephone stand having a horizontally extending shelf provided with means for attachment to a sup- 10

porting surface at its rear, of a support upon said shelf for a source of illumination, said shelf having a depending flange extending rearwardly from the front thereof, and arranged to conceal said source of illumination and deflect the rays of light downwardly. 15

In testimony whereof I affix my signature.

DAVID W. OVAITT.
